UNITED STATES PATENT OFFICE.

JOHN R. REPLOGLE, OF DETROIT, MICHIGAN, ASSIGNOR, BY MESNE ASSIGNMENTS, TO ELECTRIC REFRIGERATION CORPORATION, OF DETROIT, MICHIGAN, A CORPORATION OF MICHIGAN.

REFRIGERATED FOOD CABINET.

Application filed November 9, 1923. Serial No. 673,678.

This invention relates to refrigerated cabinets for food and the like and particularly to cabinets of the character disclosed in my United States Letters Patent No. 1,476,546.

One object of the invention is the provision of a refrigerated cabinet structure that is amply strong and rigid without being unduly heavy.

A further object of the invention is the provision of a cabinet of the character in question having a construction that lends itself readily to quantity production.

Another object of the invention is the provision of a cabinet fitted with a readily removable finishing casing, whereby handling of the cabinet in the process of manufacture is facilitated and renewal of the exterior surfaces of the cabinet after wear or injury is permitted.

A further object of the invention is the provision of a cabinet having a casing that is thoroughly sanitary.

A further object of the invention is the provision of a cabinet having a casing structure that is pleasing in appearance.

Other objects of the invention, more or less incidental or ancillary to the foregoing, will appear in the following description which sets forth, in connection with the accompanying drawings, a preferred embodiment of the invention.

In the drawings, Fig. 1 is an enlarged vertical section through the main or machine cabinet, the section being taken on the line 33 1—1, Fig. 4.

Figs. 2 and 3 are enlarged fragmentary vertical sections showing structural details of the corner construction at the top and bottom, respectively, of the cabinet structure.

Fig. 3^a is a side elevation on a reduced scale of the cabinet frame with the board wall in place.

Fig. 4 is an enlarged plan view of the main or machine cabinet with some of the parts broken away and some shown in section.

Figs. 5 and 6 are enlarged fragmentary horizontal sections showing details of the vertical corner construction of the cabinet.

Fig. 7 is an enlarged side elevation of the main or machine cabinet.

Fig. 8 is an enlarged right end elevation of the cabinet.

Fig. 9 is an enlarged section on the line 55 11—11, Fig. 4.

Fig. 10 is an enlarged fragmentary vertical section showing detailed features of the construction at the top and bottom of the tank for anti-freezing solution.

Fig. 11 is an enlarged fragmentary perspective view showing details of the cabinet frame construction at the top and bottom of the cabinet.

Fig. 12 is a plan view of the sheet steel 65 blank from which are formed the corner brackets shown in Fig. 11.

Referring in detail to the construction of the cabinet, which is designated in its entirety by the numeral 1, the same comprises 70 a rigid frame structure which is preferably made up to a considerable extent of standard structural steel forms. This frame comprises longitudinally extending bottom members 4, 4 (see Fig. 9) in the form of 75 rolled steel angles, similar longitudinal top members 5, 5, similar transverse bottom members 6, 6 and transverse top members 7, 7, said top members being supported from the bottom members by steel angles 8, 8 80 (Figs. 5, 6 and 11) at the corners of the cabinet and flat steel bars 9, 9 (Fig. 9) intermediate the ends of the cabinet. The bottom frame members 4 and 6 are rigidly connected together and to the lower ends of 85 the upright angles 8 by angle-shaped corner brackets 10, 10, and the top frame members 5 and 7 are similarly connected together and to the upper ends of the corner angles 8 by corner brackets 11, 11, said brackets 90 10 and 11 being securely riveted to the other members as shown in Fig. 11. The brackets 10 and 11 are preferably stamped from rolled sheet steel in the form shown in Fig. 12 and then bent to the form shown in Fig. 95 11. The uprights 9, 9 are preferably secured at their ends by rivets (not shown) to the bottom and top members 4 and 5 of the frame.

Within the frame above described are assembled the top, bottom and side walls of the cabinet. On reference to Figs. 3 and 11 it will be noted that both the bottom angles 4 and 6 and the top angles 5 and 7 of the frame are arranged with one side of the 105 angle horizontal and the other extending upward therefrom. On the horizontal sides of the bottom angles are arranged transverse

floor boards 12, 12 and 13 and on these floor boards are erected board side walls 14, 14, and a board right end wall 15. 16, 16 are upright partition wall boards. As viewed in Fig. 1 the said partition wall divides the cabinet into a large section at the right for food and a smaller section at the left for the compressor-condenser unit of the cabinet.

To render the walls of the food section of 10 the cabinet highly heat-insulating the floor boards are supplemented by slabs 17, 17 of sheet cork and the side wall boards 14 and 15 and partition wall boards 16 are similarly supplemented by slabs of cork 18, 18.

15 On reference to Figs. 1 and 9 it will be observed that the bottom angles 4 and 6 not only provide bottom support for the bottom and side walls of the cabinet but also adequately prevent the outward displacement of 20 said walls.

Each of the side walls 14 comprises top, middle and bottom strips 14^a, 14^b and 14^c, respectively. The strips 14^a and 14^c are cut away at their corners to accommodate 25 the corner brackets 11 and 10, respectively. The length of the strips is such that their ends do not touch the upright corner angles, thus providing end play to facilitate assembling. In assembling the boards are 30 readily inserted through the sides of the frame. First, the board 14^c is inserted, being raised out of engagement with brackets 10 to permit the necessary endwise movement, first in one direction and then the 35 other, to bring both ends of the board back of corner angles 8, 8. Then board 14^a is inserted in the same manner, being lowered away from brackets 11 to permit the needed endwise movement. Finally strip 14^b is inserted. Said strip, in conjunction with 40 brackets 11 and 10 hold boards 14^a and 14^c in place and the strip itself is sufficiently held by friction.

The board end walls of the cabinet are 45 of the same character as the side walls above described.

The top wall of the cabinet consists of a transversely extending board section 19 over the compressor-condenser unit, a timber section 20 overlying the top of the partition wall, a series of similar transverse sections 21, 21, a transverse section 22 interposed between two of the sections 21 and a transverse timber section 23 overlying the right 55 end wall of the cabinet. The top wall sections 21 and 22 are of laminated board construction and afford both adequate heat-insulating qualities and adequate strength. All of the top wall sections 19, 20, 21, 22 and 60 23 are rigidly secured to the top angles 5 and 7 by means of cap screws 24, 24 as shown in Figs. 1 and 9.

Within the heat-insulating walls of the food section of the cabinet is arranged a 65 sheet metal tank 25 for anti-freezing solu-

tion. Any known suitable solution of this character can be employed, such as brine, or a mixture of alcohol and water. I prefer to use the latter mixture rather than brine as alcohol and water solution does not attack 70 soldered joints. However, for the sake of convenience, I will refer to the solution as "brine", it being understood that this word is used in a generic sense indicating any anti-freezing solution.

The tank 25 rests upon a 75 shallow sheet metal pan 26 which is supported by the bottom insulation 17. The tank 25 has vertical end and side walls 25^a and top and bottom walls 25^b, 25^c, respectively.

The top and bottom walls are apertured to receive the ends of three pairs of vertical sleeves 27, 27^a, 28, 28^a, 29, 29^a. The ends of these sleeves are connected to the tank walls with liquid-tight joints. As shown in Fig. 10, for example, the said 85

sleeves are formed at their upper and lower ends with circumferential beads 27' and 27''. These beads form abutments for the top and bottom walls 25^b, 25^c, respectively, of the tank to permit the ends of the sleeves to 90 be flanged over on said walls as indicated. The bottom joint thus formed and preferably also the top joint are suitably soldered to render them liquid-tight. The sleeves 27, 27^a, 28, 29 and 29^a are cylindrical while the 95 sleeve 28 has straight sides with rounded corners (Fig. 4). The cylindrical sleeves are designed to form receptacles to receive cans of bulk ice-cream, or the like, say 5-gallon cans, while the flat sided sleeve 28 100 is so made to better accommodate brick ice-cream. To take the impact of the heavy ice-cream cans lowered into the sleeves, as well as support their weight, each of the sleeves is preferably provided at the lower end with 105 a heavy sheet metal pan 30 which rests upon the bottom pan 26. The top wall sections 21 of the cabinet are formed with apertures that register with the several sleeves and each of the cylindrical sleeves is fitted at 110 its upper end with a guiding or protecting thimble 31. The thimbles 31 are vertically split at 31^a as indicated in Figs. 1 and 11 and are formed at their upper ends with outwardly turned flanges. The flange of 115 each thimble is forced into a groove in the top wall section 21 and the thimble is thereby adequately supported.

In the case of sleeve 28 the top wall aperture is fitted with a thimble 32 which is similarly split at 32^a and provided with a supporting flange at its upper end. The thimble 32, however, does not extend into the sleeve 28 because the latter is fitted at its upper end with a flanged ring 33 which supports a removable sheet metal cover 34. Each of the top wall apertures of the cabinet is fitted with a cover 35 which comprises a wood ring 35^a, a sheet metal top 35^b, a sheet metal bottom 35^c, a heat-insulating core 35^d 120 125 130

of cork or the like, and a handle or knob 35^a which is secured to the sheet metal top 35^b. The sheet metal tank structure is preferably formed of sheet copper because of its non-corrodible characteristics and its high thermal conductivity. The inner cover 34 for the sleeve 28 is also preferably formed of sheet copper.

The sleeves 28, 28^a of the brine tank are spaced from the sleeves 29, 29^a to provide room for an evaporator designated in its entirety by 36. In so far as the present invention is concerned, this evaporator may be of any desired or suitable construction but 10 the one illustrated, and preferred, is like that of the refrigeration apparatus described in my pending application Serial No. 475,344, filed June 6, 1921, and in Letters Patent of France No. 547,971, to which reference may 15 be had for a detailed description and showing of the evaporator and the compressor and condenser mechanism associated with it. For the purpose of the present invention it is sufficient to note that the evaporator is of 20 the flooded type, is fitted with a float valve to admit liquid refrigerant and comprises a header 37 and a series of depending pipe loops or circulating tubes 38. One end of the header 37 is formed by a head casting 37^a having a flange 37^b which is riveted or bolted to the edge of an aperture in the adjacent side wall of the tank 25, as shown in Fig. 4, the joint thus formed being soldered to render it liquid-tight. The lower 25 ends of the pipe loops of the evaporator preferably rest on the bottom wall of the brine tank and, if desired, the evaporator can be further supported or braced from the walls of the tank by any suitable means.

30 I have provided an opening in the top wall section 22 of the cabinet so that access may be had to a filling opening which is located in the top wall of the brine tank 25 directly underneath the first named opening. These two openings are sealed by 35 means of the plugs 22^a and 25^a respectively. The tank 25 is filled with brine, through the above mentioned openings, preferably to a level somewhat below its top wall 25^b so that the major parts of the sleeves 27, 27^a, 40 28, 28^a, and 29, 29^a and the evaporator are immersed in or surrounded by the brine.

In the smaller section or compartment of the cabinet, at the left side of the partition 45 wall, as viewed in Fig. 1, is a suitable compressor and condenser mechanism designated in its entirety as 39. This mechanism, which is substantially the same as that in my pending application, Serial No. 475,344, and French Patent No. 547,971, above referred to, comprises an electric motor driven refrigerant compressor and condenser unit, together with automatic control mechanism therefor, the compressor, condenser and control mechanism being connected by suitable

refrigerant conduits with the vaporizer 36 in the brine tank. In so far as the invention herein claimed is concerned it is possible to employ any form of gas condensing and liquefying means responsive to the temperature in the brine tank. Consequently the compressor-condenser unit shown in the drawings need not be described in detail, it being sufficient to state that when the pressure rises in the vaporizer 36 to a certain point, due to the rise of temperature of the surrounding brine, the automatic control mechanism starts the compressor motor and the operation of the compressor draws the vaporized refrigerant from the vaporizer and this refrigerant is compressed and liquefied and then returned to the vaporizer as needed. The operation of the compressor reduces the pressure in the vaporizer which results in increased vaporization with resultant lowering of the temperature of the brine, and when the temperature of the brine and with it the vapor pressure in the vaporizer are reduced to a certain extent the control mechanism automatically stops the compressor motor.

The motor driven compressor-condenser unit is made readily accessible by providing the adjacent end of the cabinet with a removable closure which is preferably in the form of a sheet metal plate or panel 56. This panel is provided near its lower end with a transverse angle iron 57 which has its two ends slotted at 57^a to embrace the webs of the adjacent corner brackets 10. (Figs. 1 and 4.) At its upper end the closure 56 is apertured to receive a stud 58 carried by an angle bracket 59 secured to the transverse angle 7 of the cabinet frame. The stud 58 has its end apertured to receive a padlock (not shown). The panel 56 is readily removed by swinging its top end off the stud 58 and thereupon lifting the panel out of engagement with the webs of the corner brackets 10.

To provide adequate thickness of metal for the attachment of shipping skids and legs, metal blocks 60 are preferably secured to the under side of the frame structure at the corners of the cabinet.

To provide the cabinet with an exterior finish attractive in appearance and adapted to resist the wear encountered under the usual service conditions, I provide the lateral and top walls with removable casing parts of suitable sheet metal. The two side walls and the right end walls are thus covered with enameled steel sheets 61 and 62. Because of the excellent quality of baked black enamel I prefer its use on these sheets. The top wall of the cabinet on the other hand is covered with a continuous sheet of polished Monel metal of relatively heavy gauge. This sheet of Monel metal 63 is preferably die formed with apertures regis-

tering with the openings in the top wall sections 21, 21 and with an integrally formed depending flange 63^a extending continuously around the sheet and adapted to overlie the upper edges of the sheets 61 and 62. In forming the sheet 63 its corners are well rounded at 63^b. The upright corners of the cabinet are given a suitable finish by providing angles 64, 64 preferably of polished 10 Monel metal to harmonize with the top 63.

In applying the metal finishing sheets, the sheets 61 and 62 are secured along their lower edges by screws 65 to the bottom angles 4 and 6, while their upright edges are 15 covered by the angles 64 and with said angles secured by screws 66 to the upright corner angles 8. Similarly the edges of the plates 61 and 62 and flange 63^b are secured by screws 67 to the top angles 5 and 7 of the 20 frame. The compressor end of the cabinet is closed and finished by the sheet metal closure 56 above described and this closure plate is given a finish of black enamel uniform with that of plates 61 and 62. The finishing 25 sheets 35^b of the covers 35 are preferably formed of Monel sheet metal with polished finish like that of the top sheet 63.

By disposing the food compartments in pairs with the evaporator extending transversely between two of the pairs, as shown, I 30 secure a natural circulation of the brine which substantially uniformly affects all of the food compartments and maintains them at substantially the same temperature. I 35 have applied this construction successfully to cabinets with two pairs of food chambers, three pairs of food chambers as in the cabinet here described, and also four pairs and six pairs of food chambers, the evaporator 40 having a central position in the case of the cabinets with two, four and six pairs of food chambers.

While a properly constructed and installed 45 refrigeration apparatus such as that illustrated is capable of operating satisfactorily without attention for an indefinite period it should receive periodic inspection and it is desirable that it be readily accessible. I provide for such accessibility by mounting the 50 condenser-compressor unit in the compartment at the end of the cabinet so that it can be quickly and easily exposed by simply removing the end panel 56 without in any way hindering or preventing access to the food 55 chambers. Ice-cream cabinets must ordinarily be installed in the limited space available back of store counters or soda fountains and I have found the arrangement of the food chambers in pairs with an interposed transversely arranged evaporator and the arrangement of the compressor unit, in an end 60 compartment of the cabinet, to be one which lends itself exceptionally well to the average space limitations referred to, as well as being 65 highly satisfactory from the standpoint of

operation and inspection. Furthermore, the provision of a compartment for the compressor unit below the normal level of the top wall of the cabinet affords a corresponding unobstructed work space on the top of the 70 cabinet that the users of the cabinet find extremely convenient.

My improved form of frame construction, with removable finishing plates of sheet metal for the side and top walls of the cabinet, lends itself admirably to production on a quantity basis. The steel frame structure is readily fabricated with uniform accuracy. The wood and cork parts of the walls, cut to standard sizes, are readily assembled in the 80 steel frame. Then, after the brine tank with its enclosed evaporator and food chambers has been installed and the compressor unit has been mounted in its compartment and connected with the evaporator, the cabinet 85 can be subjected to the necessary operating tests and the cabinet rendered operatively complete before the sheet metal finishing plates are applied. These plates being applied at the very last before shipment of the 90 cabinet, all injury of the exterior finish of the cabinet in the shop is avoided and the cabinet goes to the user in perfect condition.

By standardizing the top wall sections 19, 20, 21, 22 and 23, the top wall structure of 95 cabinets having different numbers of food chambers and fitted with or without an evaporator, and with or without a compressor, is readily fabricated with a minimum number 100 of standard parts.

In the retailing of bulk and brick ice-cream and ices it has always been difficult to maintain the brick ice-cream uniformly at a temperature low enough to avoid softening of the bricks. I overcome this difficulty in 105 my improved cabinet by providing the sheet copper cover plate 34 for the food chamber 28. The heat that will enter through the cover 35 of the chamber 28 comes into contact with the copper cover plate 34 and is conducted 110 by said plate to the sheet metal tank structure from which it is absorbed by the cold brine instead of being absorbed by the ice-cream in the upper part of the chamber 28. In this way I am enabled to keep the top 115 bricks as well as the lower ones at a suitably low temperature.

In case of a rusting or corrosion or damage of the finishing plates of the cabinet, said plates, being detachably secured, can be 120 very easily renewed, thus restoring the original appearance of the cabinet at a relatively moderate expense.

In the use of the cabinet the walls of the food chambers become frosted somewhat by 125 the freezing thereon of moisture precipitated from the air. The pan 26 serves the purpose of catching any water resulting from defrosting of the walls whenever the cabinet is taken out of service and so preventing water- 130

soaking of the insulation material; and similarly the pan catches any ice-cream or the like that may be spilled in the food chambers.

5 While I have shown and described in some detail the preferred forms of construction and preferred arrangement of the parts and devices, it will be understood that in all respects there can be wide variations 10 without departing from the invention, as defined in the appended claims.

What I claim is:

1. In a refrigerated cabinet, the combination of a frame structure comprising top, 15 bottom and upright members of steel joined to form a rigid structure with rectangular sides; top, bottom, and side walls of heat-insulating material secured in the corresponding sides of said frame structure and 20 supported thereby; a food chamber within said walls, one of said walls having an opening with a movable closure to afford access to said chamber; and sheet metal finishing plates for the top and side walls of the 25 cabinet removably secured to the steel frame, the said walls of heat-insulating material being supported by the frame independently of the said finishing plates.

2. In a refrigerated cabinet, the combination of a frame structure comprising top, 30 bottom and upright members of steel joined to form a rigid structure with rectangular sides; top, bottom and side walls of heat-insulating material secured in the corresponding sides of said frame structure and 35 supported thereby; a food chamber within said walls, one of said walls having an opening with a movable closure to afford access to said chamber; sheet metal finishing plates 40 for the top and side walls of the cabinet, the top finishing plate having integrally formed depending sides overlapping the upper edges of the side plates; and means for removably securing said finishing plates 45 to the steel frame, the said walls of heat-insulating material being supported by the frame independently of the said finishing plates.

3. In a refrigerated cabinet, the combination of a frame comprising top, bottom and upright members in the form of steel angles joined to form a rigid structure with rectangular sides; top, bottom and side walls 50 of heat-insulating material for the corresponding sides of said frame secured on the inner sides of said top, bottom and upright angles; a food chamber within the said walls, one of said walls having an opening with a movable closure to afford access to 55 said chamber; and sheet metal finishing plates for said walls removably secured on the outer sides of the frame angles, the said walls of heat-insulating material being supported by the frame independently of the 60 said finishing plates.

4. In a refrigerated cabinet, the combination of a frame comprising top, bottom and upright members in the form of steel angles joined to form a rigid structure with rectangular sides; top, bottom and side walls 70 of heat-insulating material for the corresponding sides of said frame secured on the inner sides of said top, bottom and upright angles; a food chamber within the said walls, one of said walls having an opening 75 with a movable closure to afford access to said chamber; sheet metal finishing plates for the side walls of the cabinet, removably secured to the outer sides of the frame angles; and a sheet metal finishing plate for the top wall of the cabinet formed with peripheral depending flanges surrounding and removably secured to the outer sides of the top angles of the frame, the said walls 80 of heat-insulating material being supported 85 by the frame independently of the said finishing plates.

5. In a refrigerated cabinet, the combination of a frame comprising top, bottom and upright members of steel joined to form 90 a rigid structure with rectangular sides, the bottom frame members being angle forms arranged with their corners forming the lower corners of the frame; top, bottom and side walls of heat-insulating material secured in the corresponding sides of the frame structure and supported thereby, the bottom wall being supported by the horizontal sides of the bottom angles of the frame; a food chamber within said walls, 95 one of said walls having an opening with a movable closure to afford access to said chamber; and sheet metal finishing plates for the top and side walls of the cabinet 100 removably secured to the steel frame, the said walls of heat-insulating material being supported by the frame independently of the said finishing plates.

6. In a refrigerated cabinet, the combination of a frame comprising top, bottom and upright members of steel joined to form a rigid structure with rectangular sides, the bottom frame members being angle forms arranged with their corners forming the lower corners of the frame and the top 110 frame members being angle forms which are arranged with one side horizontal and the other extending upward therefrom; top, bottom and side walls of heat-insulating material secured in the corresponding sides of 115 the frame structure and supported thereby, the top and bottom walls being supported by the horizontal sides of the top and bottom angles, respectively, of the frame; a food chamber within the said walls, one of 120 said walls having an opening with a removable closure to afford access to said chamber; and sheet metal finishing plates for the top and side walls of the cabinet removably secured to the steel frame, the said walls of 125 130

- heat-insulating material being supported by the frame independently of the said finishing plates.
7. In a refrigerated food cabinet, the combination of a metal brine tank having an open-topped food chamber arranged to be surrounded by the brine; heat-insulating walls around said brine tank including a top wall having an opening registering with the food chamber; a heat-insulating movable closure for the opening in the top wall; and a supplemental inside metallic closure for the top opening of the food chamber, the latter closure having heat-conducting metal connection with the metallic walls of the brine tank.
8. A sheet metal brine tank for refrigerated cabinets having horizontal top and bottom walls formed with registering apertures, an upright sleeve having its ends extending through said apertures and formed with circumferentially extending outwardly projecting beads on the inner sides of said top and bottom walls and having its respective ends flanged outward to engage the outer sides of said top and bottom walls.
9. In a refrigerated cabinet, the combination of horizontal top and bottom walls and upright side walls; a plurality of open-topped food chambers arranged within said walls; the said top wall having openings registering with said food chambers; movable closures for the said openings; enameled sheet metal finishing plates removably secured on the side walls; a finishing plate of polished Monel metal removably secured on the top wall; and finishing plates of polished Monel metal on said movable closures.

In testimony whereof, I hereunto affix my signature.

JOHN R. REPLOGLE.
